INVENTOR

Henry P. Kraft,
By Attorneys,
Fraser, Furk & Thuyers

UNITED STATES PATENT OFFICE.

HENRY P. KRAFT, OF RIDGEWOOD, NEW JERSEY; EDGAR J. PHILLIPS AND EARL A. DARR EXECUTORS OF SAID HENRY P. KRAFT, DECEASED.

DUSTCAP.

Application filed December 19, 1919. Serial No. 346,018.

To all whom it may concern:

Be it known that I, HENRY P. KRAFT, a citizen of the United States of America, residing in Ridgewood, in the county of Bergen and State of New Jersey, have invented certain new and useful Improvements in Dustcaps, of which the following is a specification.

This invention relates to dust caps or the like, and aims to provide certain improvements therein.

The invention is particularly directed to that form of cap which is shown in a prior patent issued to me, No. 1,315,778, wherein the cap portion is formed in a plurality of longitudinally arranged parts. This type of cap marks a very considerable advance in the art, the cap being light and strong and exceedingly cheap to manufacture. I have found, however, that I can still further cheapen the structure by facilitating the operations of manufacture and assembly.

The type of cap illustrated in said patent is adapted to be secured to a tire valve or similar structure and in some cases the means of securing comprises screw-threads usually formed directly at the bottom of the cap, and either adapted to directly engage the threads of the valve, as is specifically illustrated in said patent, or to engage a clamping means having a corresponding thread.

In the construction of the cap of the patent such threads are usually stamped in the separate longitudinal sections or parts of the cap, and during the operation of assembly the threads are matched to form a continuous thread. This operation requires a careful assembly. According to the present invention I adhere to the two-part structure, but I form the screw-thread in a collar, the upper edge of which is connected to the two-part cap. This collar is preferably seamless and the thread may be formed in it either by rolling or otherwise. The upper edge of the collar is fastened to the lower edge of the cap portion, so that it forms a continuation of it. The thread thus formed may either directly engage the valve stem, or other screw-threaded part, or may provide the threads for a clamping device. By the use of such construction any precise matching is avoided, it making little difference whether the two sections of the cap

are in precise alignment at their lower edges. 55 At the same time a continuous and unbroken thread is assured.

In the drawings, wherein I have shown several embodiments of the invention,—

Figure 1 is an elevation of one form of 60 cap.

Fig. 2 is an enlarged elevation, partly in section.

Fig. 3 is a view similar to Fig. 1 partly in section showing the cap applied, the view 65 being taken at right angles to Fig. 2.

Fig. 4 is a section of Fig. 2.

Fig. 5 is an underside view of Fig. 2.

Fig. 6 is a side elevation partly in section of another form of the cap. 70

Fig. 7 is a perspective view of the cap of Fig. 1 with the wing nuts omitted.

In Figs. 1 to 5 of the drawing I have shown the invention as applied to a quick detachable cap of the type illustrated in 75 my prior patent No. 1,501,350. In these figures A indicates the cap as a whole which is shown as comprising a cap portion B and a foot portion C. The cap portion is shown as being formed of two longitudinal sections D and E (Fig. 3), and an extension F connected to the sections D and E at the lower end of the latter.

The sections D and E are best formed with overlapping flanges, as shown in said 85 patent and as illustrated in Fig. 4. The continuation F is formed as a circular band or sleeve which is best constructed from a sheet metal cup, the bottom of which is cut out, as shown at G, and the walls of which 90 are threaded, as shown at H. Such threads are preferably rolled into the sleeve, so that they are exterior as well as interior, but in the present instance the interior threads are alone utilized. The lower edges of the sections D and E are preferably flanged outwardly and then inwardly, as shown at I, and the sleeve has a corresponding flange J which overlies the flange I. The flange I rests upon an enlarged portion J' just below 100 the flange J. The flange J is preferably recessed, as shown at K K', to fit the longitudinal flanges L L' of the cap portion and also to fit the stiffening beads M M' formed longitudinally in the walls of the sections D 105 and E. This construction produces a non-rotative connection between the parts and also prevents the sleeve F from slipping

upwardly along the sections D and E. Any other suitable form of connection may be adopted, which is suitable.

In the construction shown in Figs. 1 to 5, the foot portion C is arranged internally of the cap portion instead of externally, as illustrated in my prior Patent No. 1,501,350. The foot portion is provided with flats 10 which engage the flats of the tire valve, so that as the cap is rotated to the right (for instance) the cap portion B is caused to move downwardly with relation to the foot portion C, and thus bring the clamp ring O into contact with the bevelled face P formed 15 on the cap portion, thus contracting the clamp ring O or its equivalent circumferentially and causing it to bind the valve stem or casing, as shown in Fig. 3. The bevelled face P is very conveniently formed 20 by the interior of the flange I.

The result of this construction is that no particular care need be exercised in assembling the sections D and E, since they contain no threads, and it is a matter of little 25 consequence whether their lower edges match accurately or not. If there is any inaccuracy, this is not detrimental and is covered by the flange J, which is either pressed or rolled down into position. The proper 30 formation of the thread H, however, is insured, since the sleeve being continuous, the thread may be rolled or otherwise formed without reference to any matching.

In the construction illustrated when the 35 bottom is cut out of the cup which forms the sleeve F, a flange Q is preferably left, which forms a stop for the foot portion C, so that the latter cannot be screwed out of the cap portion.

The operation of applying and removing 40 the cap from the tire valve or the like is similar to that described in the aforesaid application, it being only necessary to slip the cap over the valve stem or casing and 45 rotate the cap portion a short distance, whereupon the foot portion travels upwardly, and contracts the ring O by moving it against the bevelled face P. As soon as the clamp ring has made a contact with the valve 50 stem, so that it cannot slip along the latter, the further movement of the cap portion tends to bring the cap portion firmly against the rim nut R or the wheel felloe.

In the construction shown in Figs. 1 to 55 5 I have illustrated the cap as being pro-

vided with wings S S' which are best formed on a sleeve T, the latter being recessed to fit over the flanges of the cap portion, and being pressed into place. Such a construction provides a winged cap capable of easy 60 assembly of the wings and the cap.

In Fig. 6 I have shown the invention as applied to an ordinary screw cap, the sleeve F' being attached to the sections of the cap in a similar manner to that shown in Figs. 1 65 to 5, the internal diameter of the sleeve as compared with that of these figures being contracted so that it may directly engage the valve stem.

In both of the constructions shown the 70 ring performs the important function of holding the cap sections against any possible separation no matter how much strain is put upon the joint between the longitudinal cap sections D and E. The ring, which 75 is continuous, heavily reinforces the joint between the cap sections, and practically does away with any possibility of separation under unusual or inordinate strains.

While I have shown and described the invention as applied to several forms of caps, it will be understood that it is applicable to any device which requires to be clamped into position, as for instance, pump couplings or the like. 80

It will also be understood that I do not 85 wish to be limited to the construction herein shown and described, since various changes may be made therein without departing from the spirit of the invention. 90

What I claim is:-

1. A dust cap or the like, comprising a plurality of longitudinal sections connected together along their longitudinal edges and forming outwardly extending flanges, and a winged sleeve having notches engaging said flanges, the sleeve being fixedly carried by the cap. 95

2. A dust cap or the like, comprising a plurality of longitudinal sections connected together by longitudinal outside flanges, each section having at its lower end an outwardly extending flange, and a circular section having a flange notched to engage said outside flanges and engaging over said outwardly extending flanges. 100 105

In witness whereof, I have hereunto signed my name.

HENRY P. KRAFT.
